PICKUP TUBE

Richard C. Palmer, Pompton Plains, N.J., assignor, by
mesne assignments, to Fairchild Camera and Instru-
ment Corporation, Syosset, N.Y., a corporation of Dela-
ware

Filed Aug. 22, 1958, Ser. No. 756,687
5 Claims. (Cl. 313—65)

This invention relates to pickup tubes, and more par-
ticularly to a pickup tube which responds to infra red
radiation, and/or other radiations which may be converted
to heat.

Many pickup tubes, photocells, and similar devices are
based upon the principle that when light impinges upon
a target formed from a material known as a photocon-
ductor, the conductivity thereof changes. When a voltage
is impressed across this material, the changes in conduc-
tivity produce changes in the amount of current which is
permitted to flow. In this way, the fluctuations in the
current correspond to the impinging light.

It is frequently desired to map, view, detect or follow
objects in the absence of visible light. This result is
possible because warm but non-luminous objects emit
infra red radiation. By utilizing a pickup device which
contains target comprising a material which changes its
conductivity when struck by infra red radiations, these
changes can be caused to produce corresponding current
fluctuations.

In general, both photoconductive and infra red respon-
sive target materials have peaked response curves which
means that they respond particularly well to certain wave-
lengths, but are relatively insensitive to other frequencies.
Pickup devices having this type of response are at a dis-
advantage when the radiations to be detected are in the
insensitive range of the material's response curve.

Other target materials, such as oxides of manganese
(as used in thermistors) tend to be equally responsive to
all the frequencies in a wide spectrum. In order to utilize
these latter materials as targets they or their containers,
are blackened or otherwise caused to absorb all of the
impinging radiations. These radiations, upon absorption,
warm the target material which therefore changes its
conductivity. In the same manner as previously de-
scribed, the changes in conductivity cause changes in an
electrical current, whose fluctuations then correspond to
the impinging radiations. In this way, thermistor type
materials may be used as targets for pickup devices de-
signed to operate in complete darkness.

Unfortunately, many of the materials which are most
sensitive to infra red radiations and to heat and therefore
most desirable in the above type of pickup devices, have
an inherently low resistance (or stated in another way, a
high conductivity) in the absence of irradiation. The
application of a voltage to the "unilluminated" target
causes the flow of a "dark" current, which has a relative-
ly high amplitude. While the material's resistance is
further reduced when irradiated, the ever present high
amplitude dark current tends to mask the signal current,
and to produce an undesirably low signal-to-noise ratio.

It is therefore the principal object of my invention to
provide an improved pickup device.

It is another object of my invention to provide a pick-
up device which is more sensitive to heat and/or infra
red radiation than prior art devices.

The attainment of these objects and others will be re-
alized from the following specification, taken in con-
junction with the drawings, in which,

FIG. 1 is a diagram illustrating the relationship be-
tween various currents of a pickup tube; and

FIG. 2 is a diagrammatic representation of a pickup
tube utilizing my invention.

2

Basically my invention contemplates a novel pickup
tube wherein one electron gun supplies the dark current,
while a second electron gun supplies the signal current.
In this way, the masking effect of the dark current is
eliminated, and the signal-to-noise ratio is improved.

The problem to be overcome may be understood from
a study of FIG. 1, which shows the relationship between
currents in a prior art pickup tube. In FIG. 1 there is
illustrated a target 10 whose conductivity varies accord-
ing to "external excitation" (which is to be construed as
including infra red radiations impinging upon it), or
other radiations which change its temperature. A beam
of electrons I_b is directed toward target 10 from the cath-
ode of an electron gun. In the absence of external exci-
tation, the dark current component I_d is supplied by beam
current I_b , while the remainder I_r is returned to the out-
put circuits. When excitation strikes target 10, its con-
ductivity changes, and an additional signal current com-
ponent I_s is taken from the beam current, still further
reducing the return current I_r . It is this additional re-
duction which is of interest. The signal current com-
ponent I_s is theoretically the only variable, and therefore
the changes in I_r represent the excitation impinging upon
the target. Since the dark current component I_d is large
(for the reasons previously given), the beam current I_b
which supplies these several components, must be ex-
tremely large. The variations of the signal component I_s
are therefore only a small percentage of the beam current
 I_b , producing a low signal-to-noise ratio. In addition,
any slight variations in the dark current may be er-
roneously interpreted as a signal current.

FIG. 2 illustrates a pickup tube 12 utilizing my inven-
tion. Tube 12 contains a main gun 14, and an electron
multiplier 16 for producing an output signal from the
return current I_r . A flood gun 18 capable of producing
a beam of electrons I_f is positioned so that its electrons
are deposited uniformly on every portion of target 10.
Flood guns are well known in the art of storage tubes,
and will therefore not be discussed in detail.

My invention operates as follows. The intensity of the
electron beam from flood gun 18 is adjusted so that it is
exactly equal to the dark current. In the absence of
impinging excitations, there is no signal current, and the
current I_f from the flood gun supplies the dark current
 I_d . The beam current I_b from main gun 14 is therefore
equal to the return current I_r . When excitations impinge
on target 10 they produce a signal current I_s which is
subtracted from the beam current I_b , the reduced return
beam I_b striking electron multiplier structure 16 in the
well known manner to produce an output signal. In this
way the electron beam from main gun 14 is divorced
from the dark current, and all variations of the return
current I_r are the result of changes in the resistance of
the target. Since in my invention the beam current I_b
supplies the signal current but does not supply the dark
current, I_b can be just a little larger than I_s . Therefore,
the modulation, or variation of I_s relative to the beam
current I_b , is high thus producing a desirably high signal-
to-noise ratio.

Flood guns such as 18 usually provide a wide divergent
beam of electrons which cover the entire target. Alter-
natively, it may produce a thin electron beam which is
deflected to sweep across target 10. This alternative has
the advantage that if target 10 is not homogeneous, the
electron beam from flood gun 18 may be controlled to
deposit more or less electrons on specific areas of target
10, and thus compensate for the lack of homogeneity.

Most target materials change their conductivity with
changes in ambient temperature. These changes, of
course, affect the magnitude of the dark current. In those
cases where it is undesirable that the dark current vary

with changes in the ambient temperature, a compensating circuit 20 may be used to vary the electron beam produced by the flood gun. Circuit 20 may, for example, comprise a temperature sensitive device such as a thermocouple whose output is applied to the control grid of the flood gun.

What is claimed is:

1. An infrared pickup tube comprising: an evacuated envelope having a faceplate, a radiation sensitive conductive target on the inner surface of said faceplate, said target being adapted to produce discrete areas of greater or less resistance in accordance with the intensity of an infrared image focused thereon, said target having a sufficiently low overall resistance to produce a dark current in the absence of an image, an electron gun positioned in said envelope at a point remote from said target to direct an electron beam at said target, means whereby said gun supplies the signal current of said target, said means comprising a source of potential connected between said gun and said target; a collector electrode to receive beam electrons rejected by said target, said collector electrode being adjacent said electron gun, an electron multiplier cooperating with said second electrode, a second electron gun positioned to direct a second electron beam at said target, said second beam supplying only

20

25

said dark current; and a source of potential connected between said target and said second gun.

2. The apparatus of claim 1 wherein said second beam is divergent and deposits uniformly on every portion of said target.

3. The apparatus of claim 1 wherein said second beam is focussed and scans across said target.

4. The apparatus of claim 3 wherein the intensity of said second beam is controlled to selectively deposit electrons on specific areas of said target.

5. The apparatus of claim 1 including means to compensate for changes in said dark current due to changes in the ambient temperature at said target, said means comprising a temperature compensating circuit associated with said second electron gun and acting to control the electron beam therefrom whereby changes in said dark current due to variations in said ambient temperature are supplied by said second electron gun.
